UNITED STATES PATENT OFFICE

LELAND CLAPPER, OF TWO HARBORS, MINNESOTA, ASSIGNOR TO ROBERTS & SCHAEFER COMPANY, OF CHICAGO, ILLINOIS, A CORPORATION OF ILLINOIS

MATERIAL HANDLING MEANS

Application filed December 6, 1929. Serial No. 412,033.

This invention relates to a sand preparing and handling plant. It has for one object to provide a plant which will be wholly automatic in its operation and which will store, 5 prepare and supply sand automatically. Other objects will appear from time to time in the specification and claims.

In one form of the invention it may be applied to a locomotive sanding plant in 10 which sand is stored in one container and is automatically released from that container, treated, conveyed to a delivery container and from that container delivered, when needed, to a locomotive. Many other arrangements 15 might be adapted which would embody my invention. It is described herewith, however, in connection with the locomotive sanding plant.

My invention is illustrated more or less 20 diagrammatically in the accompanying drawings, in which—

Fig. 1 is an elevation with parts broken away and parts in section, showing a locomotive sanding plant;

25 Fig. 2 is a vertical cross section on an enlarged scale, showing in part the sand storing bin, together with the sand treating and supplying mechanism;

Fig. 3 is a vertical cross section taken at 30 an angle of 90° to Fig. 2 and showing the same general assembly of the parts;

Fig. 4 is a vertical cross section taken on an enlarged scale at line 4—4 of Fig. 2, showing the sand drum and valve assembly and 35 valve operating parts, with the sand valve open;

Fig. 5 is a sectional view taken at line 5—5 of Fig. 4, showing the main sand valve closed;

40 Fig. 6 is a vertical sectional view, taken at line 6—6 of Fig. 3, showing the sand gate and its controlling mechanism;

Fig. 7 is a horizontal cross sectional view, taken at line 7—7 of Fig. 6;

45 Fig. 8 is a transverse vertical section taken at line 8—8 of Fig. 6;

Fig. 9 is a vertical cross section showing the sand delivery storage tank with the supply controlling float in its upper position;

50 Fig. 10 is a similar view, showing the tank

largely empty, with the supplying control in the lowered position;

Fig. 11 is a horizontal cross sectional view, taken at line 11—11 of Fig. 9.

Like parts are indicated by like characters 55 throughout.

A indicates a housing for a locomotive sanding plant. It may be provided with suitable supports A¹ A¹ by means of which it is preferably positioned above the ground 60 or a foundation A². Any suitable number of locomotive tracks A³ A³ may be positioned upon the ground a proper distance from the sanding assembly.

Located within the housing A is a sand 65 storage and distribution tank or bin B. It is carried on a suitable support B¹ and is provided with one or more sand discharge tubes B². From these tubes branches B³ may be provided. Spouts B⁴ are used for final discharge of sand into a locomotive or other receptacle. The spouts B⁴ are fastened to the tubes B² or the branches B³ by joints B⁵. Such joints preferably provide for tilting 70 and rotary movement. The spouts B⁴, when not in use, are held in a raised position by cables B⁶, each of which is attached at one end to a spout B⁴, is run over a sheave B⁷, which is supported from the housing A or the supports A¹. At the opposite end of the cable 75 B⁶ one or more counter-weights B⁸ are positioned. The combined weight of the counter-weights is normally sufficient to hold the sand discharge spout in a raised position when it is not manually held in the downward or discharge position. A valve mechanism may be 80 included in the joint B⁵ by means of which flow of the sand is prevented except when the spout is in the downward position. Locomotives B⁹ B⁹ are shown as in the filling position and sand is being discharged into them. 85 B¹⁰ is an exhaust connection to permit discharge of air and dust.

C is a sand receiving and storing bin or receptacle, suitably supported, preferably in 95 a raised position, on supporting members C¹ C¹. The sand may be introduced into the bin C in any suitable fashion and by any appropriate mechanism. For the purposes of the present invention, it is sufficient that a 100

sand storage receptacle be provided and that means be provided for putting sand into it. Ordinarily the sand, as it arrives in this bin, may be moist and may have foreign matter 5 and impurities in it. The bottom of the bin C is preferably formed by a partition or dividing wall C², in which one or more openings C³ are formed for the discharge of sand from the bin. On each side of the openings 10 C³ a track member C⁴ is positioned. These members serve to carry gates or closing plates C⁵ C⁶. As shown in Fig. 3, the right hand gate is closed and the left hand gate is open. Pivoted attached at the outer end of each of 15 the gate plates C⁵ is a notched bar C⁶. C⁷ C⁷ are operating handles by means of which the gate plates C⁵ may be moved to the open or the closed position. Each of them, at its upper end, embodies a yoke C⁸ which is pivoted to a fixed support as at C⁹ and has extending across it one or more pins C¹⁰. The notched bar C⁶ lies between the arms of the yoke C⁸ and the handle C⁷ may be moved so that the pin C¹⁰ engages in one of the notches 20 of the bar C⁶.

D is a sand dryer. It is formed preferably of coiled pipe through which steam or other heating medium is circulated. The heating coil made up of the pipe, forms the receptacle 30 in which the sand is held during drying. The proportions of the coils are such that wet sand will not escape through the spaces left between adjacent coil members, whereas dry sand will escape and thus moist sand being 35 put into the dryer remains there until it has been dried and then passes out. The coil D is supported and held together by means of flange members D¹ D¹, which are fastened to the floor C² of the bin. Surrounding the 40 dryer D is a casing made up of a plurality of members D², each of which is provided with an outer flared portion D³. These members are joined together by supporting or frame members D⁴ which are themselves preferably fastened to the floor C² of the bin. The bottom of the bin itself may be provided 45 with one or more floor plates D⁵. D⁶ D⁸ are frame members extending laterally across between the supporting members C¹ C¹. Mounted upon the members D⁶ is a hopper 50 D⁷. Extending across the hopper are supports D⁸, between which screen sections D⁹ are removably positioned and supported. D¹⁰ is an air supply line, extending into the 55 hopper D⁷ and provided with perforations D¹¹ through which air may be discharged into the hopper. D¹² is a downward extension provided with a preferably upwardly facing discharge nozzle portion D¹³. By 60 means of this air supply assembly, air may be blown into the sand in the hopper at any time that it is thought necessary. D¹⁴ is a gate plate movably positioned and adapted in one position to close the discharge from the 65 hopped D⁷ and in another to open it. D¹⁵

D¹⁵ are track members preferably fastened to the bin D⁷ adjacent its bottom discharge opening. These track members may be made up of angles, channels or I-beams, or any suitably flanged member. In general the 70 gate is supported upon and runs along the laterally extended flanges as indicated particularly in Fig. 6. Fastened to the gate are two tubular members D¹⁶. D¹⁷ D¹⁷ are rods, one lying within each of the tubular members 75 D¹⁶. The rods D¹⁷ are joined at each end to each other by means of cross members D¹⁸, which, by means of turn buckles D¹⁹ D²⁰, are fastened to cables, the turn buckle D¹⁹ being fastened to a cable D²¹ and the turn buckle 80 D²⁰ being fastened to a cable D²². The track members D¹⁵ are provided with one or more oppositely positioned perforations D²³ through which a pin D²⁴ may be inserted. The pin is provided with a chain D²⁵ by means of which it is fastened to the bin D⁷ to prevent loss or misplacement. D²⁶ are gate stops. 85

E is a housing provided with an enlarged hopper-like portion E¹, above or within 90 which is positioned a screen section E². The housing E is provided with an opening F³ which is preferably positioned beneath the discharge opening from the hopper D⁷. The housing E is also provided with a discharge chute portion E⁴ which is positioned to discharge over a partition E⁵ into a refuse bin E⁶. The hopper portion E¹ and the screen housing and screening parts are all supported from a drum E⁷, the hopper E¹ discharging 95 through a restricted passage E⁸, past a valve construction which will be described below, into the drum E⁷.

The restricted passage E⁸ is formed in a member F which is provided with a laterally extending flange F¹ which is itself supported from a valve housing member F² which is divided by means of a partition F³ and is provided with an upper laterally extending flange F⁴ which is fastened to the flange F¹, 105 and a lower laterally extending flange F⁵ which is fastened to the drum E⁷. By means of these parts the screen E² and its associated parts are supported from and adapted to move with the drum E⁷. The valve partition member F³ is bored out as at F⁶ and is further provided with a bored out portion F⁷ which is preferably pointed upwardly. The passage through the housing F² is thus subdivided into the two channels F⁸ F⁸. F⁹ is 110 a valve member generally conical in shape and provided with a reduced portion F¹⁰ which latter is positioned within the bore F⁷. Positioned about the conical portion F⁹ is a generally conical rubber gasket member F¹¹ 115 and positioned about it and partially overlying it is a metallic, conical member of somewhat lesser size F¹². The conical metallic member and the conical rubber gasket are 120 removably held in position by a screw F¹³. 125

G G are a pair of generally vertically extending supporting members carried upwardly from any suitable foundation. G¹ is a link adapted to steady the drum in its movement.

5 G² G² are bent lever arms pivoted adjacent the upper end of the members G as at G³. At one end, the lever arms G² G² are pivotally joined to the drum E' as at G⁴. At their opposite ends they are joined by an adjustably positioned cross member G⁵ which may 10 be of such size or weight as to serve as a counterweight member. Fastened preferably centrally of this member is one end of the cable D²². The levers G² G² are slotted as at G⁶ and by means of bolts G⁷ G⁷ the cross member G⁵ may be adjusted in or out to vary the 15 leverage which its weight exerts upon the lever arm G². G⁸ is a sheave provided with a yoke G⁹ which is attached by a chain G¹⁰ to the foundation A². The sheave G⁸ is positioned adjacent the drum and beneath the cross member G⁵. The yoke and the chain are 20 of sufficient weight to act as a counterweight to keep the cable D²² tight. G¹¹ is a post to limit the counterweight.

25 Extending laterally from the member F² and joining the bore F⁸ is a pipe H. It is connected to a union H¹ from which a section of pipe H² extends downwardly into the drum E'. A second section of pipe H³ extends to a valve housing H⁴. A third section of pipe H⁵ extends upwardly from the union H¹ and is fastened to a T H⁶, the upper end of which is closed by a plug H⁷. Fastened to the T is a pipe section H⁸ which by suitable elbows and other connections is carried downward about the drum E' and finally penetrates the drum and terminates in a nozzle part or section H⁹.

30 I is a pipe positioned within the drum E' in general alignment with the nozzle part H⁹ of the pipe H⁸. It extends outwardly through the top of the drum E' and by means of the laterally extended member I¹ it is attached to a flexible section I². This flexible section is joined to the rigidly mounted pipe I³ which extends upwardly and terminates in a downwardly bent portion I⁴ which penetrates into and is adapted to discharge into the bin B.

35 Within the valve housing H⁴ is positioned a valve J. It is provided with two ports J¹ and J². The valve is a three-way valve, the valve housing being provided with a port J³ to which the pipe section H⁵ is provided, a port J⁴ to which the air intake J⁵ is provided and a port J⁶ to which the exhaust J⁷ is provided. The intake section J⁵ may be provided with air from any suitable source by 40 means of a flexible pipe or hose J⁸ and the exhaust section J⁷ may be attached to a pipe section J⁹ which may be flexible or formed in any other suitable manner.

The valve member J is formed with an extension J¹⁰ which extends laterally beyond

the valve body. To this is attached an operating handle K. Pivotally attached to the handle K is a valve operating rod K¹. It is threaded throughout a considerable length towards its lower end as at K². K³ is a member 70 fastened on one of the supports G and provided with a laterally extending part, as shown, which is perforated as at K⁴. Through this perforation the threaded portion K² of the rod K¹ penetrates and is adapted to move freely. Two or more pairs of nuts K⁵ K⁶ are adjustably positioned on the threaded part K² of the rod K.

L is a cover mounted on the upper end of the bin B and may be provided with a separate portion L¹ through which the supply pipe I⁴ penetrates and to which it may be attached. Positioned for rotation on the cover is a sheave L². The cable D²¹ runs in this sheave and is fastened to a tubular section L³ which is positioned about the pipe I⁴ and is of such size that it can move freely up and down upon it. Fastened to the member L³ and extending downwardly and outwardly from it is a plurality of rods L⁴. These rods 80 are fastened to the tubular section L³ preferably adjacent its upper end. Adjacent the lower end of the tubular member L³ is a plurality of downwardly and outwardly extending rods L⁵. All of these rods engage and support a ring-like member L⁶. The member made up of the tubular section L³, the ring L⁶ and the rods L⁴ and L⁵ may be called a float because it will always rest upon the top of the sand within the bin. L⁷ L⁷ are rods 90 extending transversely across the bin and serving as a downward limit beyond which the float cannot move. The float is shown in this full downward position in Fig. 10, where it is shown as resting upon the stops L⁷.

100 It will be realized that while I have shown a practical and operative device, many changes might be made in the size, shape, number and disposition of parts without departing from the spirit of my invention. Particularly the invention might be embodied in a plant designed for supplying material other than sand, and for supplying liquid instead of solid material.

110 The use and operation of my invention are 115 as follows:

In Fig. 1, the bins C and B are full of sand. The gate D¹⁴ is closed and sand is not being discharged into the drum E'. As shown in 120 that figure, two locomotives have just commenced withdrawing sand from the tank B. As this is done the level of sand in that tank will lower and the float will be lowered with the falling level of material. When this movement has continued sufficiently, the cable D²¹ will be pulled sufficiently to open the gate D¹⁴. Sand will be discharged from the hopper D' upon the screen E² and will pass over the part E¹ through the restricted opening E⁸ and into the drum. At the time that 125

130

loading of the drum starts, it is in the raised position, as indicated particularly in Fig. 2, and the valve parts are in the position which they occupy in full lines in Figs. 2, 3 and 4. When the drum is largely full, it will overbalance and fall to the dotted line position indicated in Fig. 2. This movement raises the lever G^2 to the position shown in dotted lines in that figure; draws upon the cable D^{22} , closes the gate D^{14} and raises the float I^4 to approximately its upper position. The falling movement of the drum changes the valve setting and causes air pressure to be applied to the interior of the drum. This air under pressure is thus discharged through the nozzle part H^9 into the pipe I and from the drum and through this pipe sand is raised through the pipe I^8 and discharged into the bin B . This operation continues as long as the drum is in the lowered position. When the drum has been largely emptied, the leverage of the parts G^2 and G^5 is sufficient to raise the drum again to the full line position of Fig. 2. The parts have thus again reached the position which they occupy in Fig. 1 and if the level of the sand in the bin B is sufficiently high to support the float at or near its upper limit, the parts will remain stationary. If withdrawal of sand from the bin B has continued during this time, it may be that the level of the sand is not sufficient to support the float at or near its upper position. Since it is the weight of the drum and the sand which as it falls initially raises the float and holds it in the raised position, it is clear that as soon as the drum raises itself, it can no longer hold the float in a raised position and if the level of the material in the bin B is not sufficient to do so, the float will fall entirely and rests upon the top of the material in the bin or upon the stops L^7 , and this falling movement of the float will again open the gate D^{14} and will start the filling and emptying cycle of the drum. Thus the drum will automatically continue to be filled from the bin C and discharged into the bin B , so long as the level of the material within the bin B is not sufficiently high to support the float so that its weight does not become effective to open the gate D^{14} . Whenever the float can fall sufficiently to open the gate D^{14} it will do so, provided that at the same time the drum is itself not in the lowered position. The cycle of automatic operation by means of which the bin B is constantly filled is, therefore, controlled by the withdrawal of material from that bin and the consequent lowering of the float.

As mentioned above, the valve F^9 F^{10} is shown in Fig. 4 in the position in which sand may be fed past it into the drum. When the air valve controlling handle and the air valve are moved into the position indicated in dotted lines in Fig. 4 and the exhaust connection J^9 is closed, air pressure passes through the

pipe H^8 , the union H^1 and the pipe H into the bore F^6 F^7 and seats the valve F^9 in the position shown in Fig. 5. This prevents escape of pressure from the drum and permits the air pressure to raise the sand from the drum into the dispensing bin. 70

When the parts are restored to the position indicated in full lines in Fig. 4, the exhaust connection J^9 is opened, pressure within the drum is relieved and the valve F^9 is again free to resume the position indicated in Fig. 4. 75

In the operation of the sand dryer, sand, as it dries, falls between the pipe sections and will fall onto the elements D^2 . The proportion of these elements is such and the size and relative location of the openings between them is such, that any sand which falls upon them and piles up upon them will reach its angle of repose before it can pass through the opening between the members and thus an escape for moisture is provided between the elements D^2 but sand cannot pass out at the same place. 80

I claim:

1. In combination in a material handling plant, a receiving bin, a dispensing bin, and automatic means for conveying material from the receiving bin to the dispensing bin, said means including a third receptacle movably mounted and adapted to be filled from the receiving bin and to be discharged into the dispensing bin and to move to control the discharge of material into the dispensing bin. 95

2. In combination in a material handling plant, a receiving bin, a dispensing bin, and automatic means for conveying material from the receiving bin to the dispensing bin in response to emptying of the dispensing bin, said means including a third receptacle movably mounted and adapted to be filled from the receiving bin and to be discharged into the dispensing bin and to move to control the discharge of material into the dispensing bin. 100

3. In combination in a material handling plant, a receiving bin, a dispensing bin, and automatic means for conveying material from the receiving bin to the dispensing bin, said means including a third receptacle movably mounted and adapted to be filled from the receiving bin and to be discharged into the dispensing bin, said means being automatically controlled by the variation of level of material in the dispensing bin and to move to control the discharge of material into the dispensing bin. 115

4. In combination in a material handling plant, a receiving bin, a dispensing bin, and automatic means for conveying material from the receiving bin to the dispensing bin in response to emptying of the dispensing bin, said means including a third receptacle movably mounted and adapted to be filled from the receiving bin and to be discharged into the dispensing bin. 125

dispensing bin, said means being automatically controlled by the variation of level of material in the dispensing bin and to move to control the discharge of material into the dispensing bin.

5. In combination in a material handling plant, a receiving bin, a dispensing bin, and automatic means for conveying material from the receiving bin to the dispensing bin in response to emptying of the dispensing bin, said means including a third receptacle adapted to be filled from the receiving bin and to be discharged into the dispensing bin, and means for filling it and discharging it into the dispensing bin, said means being automatically controlled by the variation of level of material in the dispensing bin.

6. In combination in a sand handling assembly, a sand storage bin, a sand delivery tank, means for discharging sand from said tank, means for automatically re-filling said delivery tank in response to the withdrawal of sand therefrom, said means including a movably mounted receptacle adapted to receive sand.

7. In combination in a sand handling assembly, a sand storage bin, a sand delivery tank, means for discharging sand from said tank, means for automatically re-filling said delivery tank in response to the withdrawal of sand therefrom, said means including a movably mounted receptacle adapted to receive sand and means for moving sand from said receptacle to said storage bin.

8. In a sand handling assembly, a storage bin, a movably mounted sand drum adapted to receive sand, a sand delivery bin, selective sand delivery connections from said bin, a float member movably positioned within said bin, adapted to move in response to variations of the sand within said bin, a gate controlling the discharge into the drum, the float adapted by its lowering movement to open the gate, the drum adapted to close the gate in response to its own downward movement.

9. In a sand handling assembly, a storage bin, a movably mounted sand drum adapted to receive sand, a sand delivery bin, selective sand delivery connections from said bin, a float member movably positioned within said bin, adapted to move in response to variations of the sand within said bin, a stop to limit the lowering movement of the float within the bin, a gate controlling the discharge into the drum, the float adapted by its lowering movement to open the gate, the drum adapted to close the gate in response to its own downward movement.

10. In a sand handling assembly, a storage bin, a movably mounted sand drum adapted to receive sand, air connections to said drum, an automatic valve operating mechanism adapted to control said air connections and to be operated automatically by movement of the drum, a sand delivery bin, selective sand

delivery connections from said bin, a float member movably positioned within said bin, adapted to move in response to variations of the sand within said bin, a gate controlling the discharge into the drum, the float adapted by its lowering movement to open the gate, the drum adapted to close the gate in response to its own downward movement.

11. In a sand handling assembly, a storage bin, the bin arranged to discharge into a second bin adapted to receive sand and air pressure elements within said second bin, a movably mounted sand drum adapted to receive sand, air connections to said drum, an automatic valve operating mechanism adapted to control said air connections and to be operated automatically by movement of the drum, a sand delivery bin, selective sand delivery connections from said bin, a float member movably positioned within said bin, adapted to move in response to variations of the sand within said bin, a stop to limit the lowering movement of the float within the bin, a gate controlling the discharge into the drum, the float adapted by its lowering movement to open the gate, the drum adapted to close the gate in response to its own downward movement.

12. In combination in a material handling plant, a receiving bin, a dispensing bin, and automatic means for conveying material from the receiving bin to the dispensing bin in response to emptying of the dispensing bin, said means including a third receptacle adapted to be filled from the receiving bin and to be discharged into the dispensing bin, said means including a float member mounted within the dispensing bin, adapted to fall with lowering of the level of material within that bin.

13. In combination in a material handling plant, a receiving bin, a dispensing bin, and automatic means for conveying material from the receiving bin to the dispensing bin in response to emptying of the dispensing bin, said means including a third receptacle adapted to be filled from the receiving bin and to be discharged into the dispensing bin, and means for filling it and discharging it into the dispensing bin, said means including a float member mounted within the dispensing bin, adapted to fall with lowering of the level of material within that bin.

14. In combination in a material handling plant, a receiving bin, a dispensing bin, and automatic means for conveying material from the receiving bin to the dispensing bin in response to emptying of the dispensing bin, said means including a third receptacle adapted to be filled from the receiving bin and to be discharged into the dispensing bin, and means for filling it and discharging it into the dispensing bin, said means being automatically controlled by the variation of level of material in the dispensing bin, said

automatic control including a float member positioned within the dispensing bin, adapted to fall with a lowering of the level of material in that bin and adapted in its fall to initiate discharge of material to said third receptacle.

15. In a material handling plane, a receiving receptacle and a dispensing receptacle and means for supplying the dispensing receptacle from the receiving receptacle, said means including a third receptacle, the latter being movably mounted, and a float element in the dispensing receptacle, air conveying means adapted to convey material from the third receptacle to the dispensing receptacle, the third receptacle being movably mounted and adapted, when in one position, to receive material from the receiving receptacle and by reason of its movement to cut off the air supply, adapted in another position to cut off the material supply to it and turn on the air supply.

16. In combination in a material handling plant, a receiving receptacle and a dispensing receptacle, means for supplying the dispensing receptacle from the receiving receptacle and automatic means for controlling this supply in response to withdrawal of material from the dispensing receptacle, said means including a third receptacle mounted to rise and fall, the latter receptacle positioned to rise automatically when substantially empty and to fall automatically when substantially filled with material, parts associated with said third receptacle adapted when it falls automatically to cut off the supply of material to it and automatically to initiate discharge of material from it to the dispensing receptacle.

40 17. In combination in a material handling plant, a receiving receptacle and a dispensing receptacle, means for supplying the dispensing receptacle from the receiving receptacle and automatic means for controlling this supply in response to withdrawal of material from the dispensing receptacle, said means including a third receptacle mounted to rise and fall, the latter receptacle positioned to rise automatically when substantially empty and to fall automatically when substantially filled with material, parts associated with said third receptacle adapted when it falls automatically to cut off the supply of material to it and automatically to initiate discharge of material from it to the dispensing receptacle, and a float positioned in the dispensing receptacle and adapted, when free to move, to fall in response to lowering of the level of material in the dispensing receptacle and means operated by movement of the float to initiate discharge of material to the movably mounted receptacle.

65 18. In combination in a material handling plant, a receiving bin, a fixed dispensing bin, and automatic means for conveying material

from the receiving bin to the dispensing bin in response to emptying of the dispensing bin, said means including a third receptacle adapted to be filled from the receiving bin and to be discharged into the dispensing bin, and means for filling it and discharging it into the dispensing bin, said means being automatically controlled by the variation of level of material in the dispensing bin.

Signed at Two Harbors, county of Lake 75 and State of Minnesota, this 23 day of November, 1929.
